UNITED STATES PATENT OFFICE.

HAROLD ROWNTREE, OF KENILWORTH, ILLINOIS, ASSIGNOR TO NATIONAL PNEUMATIC COMPANY, OF NEW YORK, N. Y., A CORPORATION OF WEST VIRGINIA.

RAILWAY BLOCK SYSTEM.

1,278,221.

Specification of Letters Patent. Patented Sept. 10, 1918.

Application filed July 14, 1915. Serial No. 39,761.

To all whom it may concern:

Be it known that I, HAROLD ROWNTREE, a citizen of the United States, residing at Kenilworth, county of Cook, State of Illinois, have made a certain new and useful Invention in Railway Block Systems, of which the following is a specification.

This invention relates to railway block systems, and particularly to systems for securing safety of operation of cars or trains over the same tracks.

The object of the invention is to provide a control system for the operation of cars or trains whereby the speed of travel of a car or train is controlled by that of a car or train operating in advance of it over the same track.

A further object is to provide a system wherein the speed of a car or train is automatically controlled by that of a preceding car or train operating over the same track.

A further object is to provide a system wherein the speed of a car or train is automatically controlled by the distance ahead of a preceding car or train operating over the same track.

A further object is to provide a system wherein the speed of a car or train is automatically controlled by the conjoint action of the speed and distance ahead of a preceding car or train operating over the same track.

A further object is to regulate and control the speed of a car or train by that of a preceding car or train operating over the same track, in such manner as to prevent the approach of the trains to a closer proximity than a predetermined distance apart.

Other objects of the invention will appear more fully hereinafter.

The invention consists substantially in the construction, combination, location and relative arrangement of parts, all as will be more fully hereinafter set forth, as shown in the accompanying drawings, and finally pointed out in the appended claims.

Referring to the drawing,—

Figure 1 is a view in circuit diagram showing one form of car or train speed control system embodying the principles of my invention.

Figs. 2 and 3 are similar views showing other arrangements for carrying out my in-

vention and embodying the broad principles thereof.

55

Fig. 4 is a diagrammatic view illustrating a portion of the arrangement employed in connection with the system shown in Fig. 3.

The same part is designated by the same reference numeral wherever it occurs 60 throughout the several views.

While I have shown, and will describe, my invention as applied to the operation of cars coupled up into trains it is to be understood that the invention is equally well 65 adapted for use in connection with the operation of single cars, and therefore, wherever I refer to a car, or to a train, it is to be understood that in either case a single car or two or more cars coupled up into a train is 70 intended and included.

In the operation of railway systems, including elevated and subway systems, the increase of passenger traffic has required the 75 operation of increased numbers of cars or trains over the same track and at a greatly reduced headway or distance apart of adjacent trains in order to handle the traffic. In order to secure safety of operation of the cars or trains under the conditions of increased numbers of the trains and reduced 80 headway between them or distance apart of succeeding trains, as well as the desired speed of operation which the demands for rapid transit require, it has been necessary to 85 employ block systems to prevent rear-end collisions, and to refine such systems to a point which will insure safety of operation with a very narrow margin of space or time interval apart between adjacent trains.

90

In the automatic block systems now most generally adopted in practice, the fundamental principle is employed of automatically stopping a train when it reaches any one of certain fixed points unless the preceding 95 train has passed a certain fixed point a predetermined distance ahead. This predetermined distance is ordinarily based, as its minimum upon something over twice the distance the train would travel after application of the emergency brakes when going at full speed. If, for example, a train running at full speed could be stopped in 500 yards by the emergency brakes then if the fixed emergency stops were placed 500 yards 100 apart a train that had its power cut off and

105

the emergency brakes applied automatically at one fixed emergency stop, would be brought to rest when opposite the next fixed emergency stop. If, however, the preceding 5 train had stopped, through accident or otherwise, immediately after passing the latter mentioned fixed emergency stop when the following train would be in danger of crashing into it before it finally stopped, and 10 therefore this distance apart of the fixed emergency stops is made somewhat greater than the distance of travel of a train in stopping, so that if we assume it takes 500 yards travel to stop a train on the emergency 15 brakes, then the fixed emergency stopping points will be placed perhaps 700 yards apart. Furthermore, as the following train has no means of knowing whether the preceding train has only just passed the fixed 20 emergency stopping point next ahead or not it would be manifestly unsafe for the automatic stopping appliance to be put out of operative condition at any fixed emergency stopping point until the preceding train has 25 passed the second fixed emergency stopping point ahead so that there would be under all conditions one full distance of 700 yards that would be dead to an approaching train until the next section of 700 yards had been 30 made dead. This means that when such systems are used trains cannot be operated nearer together under any circumstances than the distance apart as predetermined above stated as a minimum, which is a distance consider- 35 ably over twice the distance the train would travel after application of the emergency brakes when going at full speed.

However, the congestion of traffic at nearly all points on some railway systems at cer- 40 tain hours of the day, and on all roads at certain points at certain hours of the day, requires that trains be operated nearer together or with less headway than the limitations of present block systems will allow, 45 where the congested traffic is to be handled properly and expeditiously. But in the reduction of headway or distance between trains the necessity for safety of operation to prevent collisions increases, and systems 50 at present in use afford no adequate degree of safety of operation of trains nearer together than the present predetermined distance apart of the trains as determined in the manner above explained, will permit.

55 It is among the special purposes of my present invention to provide a system wherein trains may be operated as closely together as may be desired and yet with perfect safety, and this purpose is accomplished, in 60 accordance with my present invention, by providing means whereby the maximum limit of speed of a train is made to depend upon the speed at which the preceding train on the same track is operating, or the distance ahead of the preceding train, or both

the speed and distance ahead of the preceding train.

It is obvious that if, in accordance with my invention, the speed at which a train is running is automatically reduced as the 70 speed of a preceding train is reduced, the two trains may be run at full speed as close together as might be desired and with perfect safety since the train in advance could not stop any more quickly than the rear 75 train is automatically stopped, and consequently when the front train stops the rear train will also be stopped automatically and at a distance away from the front train which would be the same distance at which 80 the train had been running when running at full speed. Furthermore, if the front train is running at a slow speed and the rear train at a high speed, then, in accordance with my invention, the speed of the rear train is 85 automatically reduced as it approaches the preceding train until its speed equals that of the preceding train, and consequently the farther away the rear train is from the preceding train the faster it can be run with safety, 90 since, in accordance with my invention, the speed of the rear train will be automatically reduced as it approaches nearer and nearer the preceding train, until the speeds of the two trains are equal. From this it will be 95 seen that the faster the preceding train is operated the faster the rear train may also be operated with safety.

In carrying out my invention, and particu- 100 larly in the application thereof to elevated and subway railway systems, the distance apart, in time intervals, of adjacent trains may be taken as the average stopping time at a station, although trains may be operated in accordance with my invention at a consider- 105 able less time interval apart than the average stopping time at a station, but, manifestly no gain in time or in carrying capacity would result with a less time interval be- 110 tween trains than such average station stop- ping time.

In the arrangement shown in Fig. 1 as diagrammatically illustrating one form of embodiment of my invention, I employ an additional conductor, such as a third rail, trolley wire, or the like, which, for the pur- 115 poses of distinction I will call the sectional rail, and which is indicated at 17. This rail is divided up into, or is, composed of sepa- 120 rated sections of such relation that a contact shoe 18, at the front end of the train, which co-operates with said conductor, passes onto a section of the conductor 17, before a sim- 125ilar shoe 19, at the rear end of the train passes onto the next rearward section of said conductor. It is to be understood, as before explained, when I refer to the front and rear ends of a train I intend, also, to include therby not only a train composed of sev- 130 eral cars but also a single car. And in case

of a train of several cars it is immaterial so far as my invention is concerned, whether the equipment of each car is the same, as is the usual practice, or whether the apparatus concerned in carrying out my invention is located only at the front and rear ends of the entire train. Where several cars are coupled up in a train the equipment on the intermediate cars is to be cut out of service 10 in any suitable or convenient manner. For convenience of description, therefore, I shall describe the equipment and operation as though the train consisted of a single car, it being understood that the invention is 15 equally applicable to a train of two or more, or any number of cars. I shall also omit illustration and description of the car propelling motors, the brake mechanism and other essential equipment required in the operation of cars or trains, as all such devices are well known in the art and they do not constitute my present invention.

Carried by the train is a suitable device 1 the operation of which is dependent upon 20 the speed of travel of the car. In the form shown, as illustrating the principles of my invention, a speed actuated device similar to the sliding collar of a centrifugal ball governor is employed, which device is driven 25 by the car propelling motor, the car axle A, or other suitable or convenient moving part. An arm 2 is connected with the governor device 1 and arranged to be moved thereby into positions corresponding to the extent of 30 actuation of the governor device, that is, corresponding to the speed of travel of the train. The arm 2 carries a conductor portion 3 which operates over and in contact with the conductor strips 4, 5, 6. The strip 35 4 is a continuous strip while the strips 5, 6, are each made up of sections, each section being electrically connected to its next adjacent section through a resistance indicated at R. The conductor strip 4 is in electrical 40 connection through wire a with the main trolley or third rail contact 20, the latter operating on the trolley or third rail conductor 21, in the usual manner to supply current to the car propelling motor (not 45 shown) through the controller E in the usual manner. One end of the sectional strip 6 is in electrical connection through wire b with the auxiliary contact member 19 at the rear end of the train. The corresponding end of 50 the sectional strip 5, is included in a circuit c which contains the coils of a solenoid 7, and which circuit is grounded, as at G. The auxiliary contact member 18 at the front end of the train is included in a circuit d which 55 55 contains the coils of a solenoid 8, and which circuit is grounded as at G. If desired a suitable current operated indicator 22, may also be located in the circuit d, for a purpose to be more fully explained hereinafter.

60 65 The relation of the arm 2, and speed gov-

ernor device 1 is such that the slower the train is moving, and therefore the slower the governor device is operating, the nearer the contact portion 3 of arm 2 will approach the ends of the strips 5 and 6 which are respectively connected to the solenoid 7 and auxiliary contact member 19, and the nearer the contact member 3 approaches said ends of contact strips 5, 6, the fewer of the sections thereof will be included in the circuit 70 of said conductor portion 3, and hence the less will be the resistance included in said circuits, and consequently the greater will be the flow of current from the main trolley or line through solenoid 7, and from the 75 main trolley or line to the rear auxiliary contact member 19, and into the section of the auxiliary sectional conductor 17, with which said member 19 happens at the moment to be in contact. As above indicated 80 the conductor 17 is divided up into sections, and the sections thereof should be of such maximum length that the front and rear contact members 18 and 19 are never in contact with the same section, the front 85 member 18 entering upon a new section before the rear member enters upon the section from which the front member has just passed. The sections of the conductor 17 are connected together electrically through 90 a resistance, the connection being controlled by a suitable switch. For illustrative purposes I have shown a switch in the form of a bent lever pivotally mounted intermediate 95 the arms thereof upon or adjacent one section of conductor 17, one arm 9 of the lever carrying an insulated contact 11, which cooperates with contact 12 on another adjacent section of the conductor to complete circuit 100 connection through a resistance 13 to the 105 first mentioned conductor section. The contacts 12 should be so arranged as to normally retain the contact 11 in engagement therewith while, at the same time permitting the ready separation of said contacts; and 110 the contact 11 should be so constructed as to require that it be forced fully to closed and retaining position upon contacts 12 before the circuit connection is completed, thereby preventing closure of the circuit connection 115 through accidental jarring of the contact 11 toward the contacts 12. This is accomplished by providing the contact 11 with an insulated point 10.

Each switch device is provided with suitable lugs or rollers 14, 15, one on each of the bent arms of the switch, and respectively on opposite sides of the pivot of said switch, the said lugs or projections extending upwardly into the path 120 of the contact members 18, 19. That is to say, the contact member 18 is provided with a lug or roller, indicated at B, which, as said member passes by a switch device, engages the lug or roller 14 thereon and opens 125 130

the switch, while the member 19 has a lug or roller C, which engages the lug or roller 15 on each switch device, as it passes by said device, and closes the switch.

5 The solenoids 7, 8, act in opposition to each other, upon a switch device 16, the solenoid 7 operating to close said switch while the solenoid 8 operates to open it. The switch device 16 opens and closes a circuit which includes means, well known in the art, for releasing the automatic brakes of the train, for starting the train controller in operation to start the train, if the latter is at rest, and for accelerating the speed of the 10 train if the latter is in motion. As such control devices are common in the art I have not shown them in detail but have indicated such a device at D, as being included in a circuit which is opened and closed by the 15 switch device 16. In the use of a control device D, as is customary, if the motorman's controller E is in "off" position, then the closing of the switch 16 does not release the brakes or start the train, but if the motorman's switch is in running position then closing the switch D, will start the train and accelerate its speed until it corresponds to the position of the motorman's controller in the usual way. In other words the function 20 of the device D is to stop the train altogether or else to cut down its speed or accelerate it, but in no case can it cause the train to run faster than the motorman desires.

35 I will now describe the operation of the system.

Suppose a train is running at any given speed. The rheostat arm 2 on said train will occupy a corresponding position dependent 40 upon the speed at which the train is running and therefore the current from the main line through shoe 20, circuit a, contact strip 4, conductor 3, rheostat 6, circuit b, contact member 19, at the rear end of the train, and 45 thence to the sectional conductor, will continue to flow through successive sections of the conductor 17, in the direction opposite that of the travel of the train, and through the successive resistances 13, as well as 50 through such portions of the resistance R, of the rheostat as may be determined by the position of the arm 2, that is, as may be determined by the speed at which the train is running. The greater the speed 55 of the train the greater will be the resistance R cut in to this circuit. The current thus delivered to the sectional conductor 17 cannot flow along said conductor in the same direction as that of the travel 60 of the train because the switch device which connects adjacent sections of said conductor in advance of the rear contact member 19 has been opened, by the passage thereof past of the front contact member 18, as 65 above explained, it being remembered that

all the switches to the rear of contact member 19 have been closed by the action of said member moving therepast. The current thus delivered to the conductor 17, will flow along said conductor 17 in a direction opposite to that of the travel of the train till it reaches the front contact member 18 of the next succeeding train operating along the same track, said current passing successively through the various resistances 13 of the intervening switches. The number of these resistances traversed by the current before it reaches the front contact 18 of the next succeeding train will, of course, depend upon the distance apart of the trains. Thus it will be seen that the total resistance of the circuit of the current supply from a preceding to a succeeding train is dependent not only on the speed of the preceding train, which controls the rheostat resistance R of 80 that train, but also on the distance apart of the trains, which determines the number of intervening resistances 13. Consequently the strength of the current supplies through the solenoid 8 of the succeeding train depends upon the speed of travel and distance in advance of the preceding train. The current passing through the co-operating solenoid 7 of the succeeding trains is controlled entirely by the speed of that train 85 through the resistance of the rheostat strip 5. Consequently the switch device 16, and hence, also, the circuit of the control device D, is under the joint control and reciprocal action of the solenoids 7, 8, the solenoid 7 90 operating more strongly to maintain the switch device 16 closed the slower the rear train is running, and less strongly, the faster said train is running, while at the same time, and conversely, the solenoid 8, operates more 95 strongly to open said switch device the slower the preceding train is running, or the nearer the two trains are to each other, and less strongly when the faster the preceding train is running or the greater its distance in advance of the succeeding train.

Thus it will be seen that two resistance conditions obtain in the circuit which supplies current to the solenoid 8 of a succeeding train, namely, that due to the number 100 of resistance coils 13 between it and the preceding train, that is, the distance apart of the trains, and that due to the speed of the preceding train. This means that the switch 16 will open whenever the speed of 110 the rear train brings it into too close proximity to the front train, taking into consideration both its own speed and both the speed and the distance ahead of the front train, and the opening of the switch 16, will 115 cause the immediate and automatic slowing down of the rear train until the reduction of speed thereof has so affected its governor 1 and rheostat arm 2, and the resistance R of the strip 5 thereof, as to cause the current 120

passing through the solenoid 7 to overcome the action of solenoid 8, and thereby again close switch 16. Thus the rear train is automatically brought to a safety point of 5 operation with reference to the speed and distance ahead of the preceding train.

It will be seen, from the foregoing description, that so long as the front train is far enough ahead of the rear train, or is 10 running at a sufficient speed, when its distance ahead is considered, the rear train remains under the full control of the motorman, and can be stopped, started, and operated at any desired speed wholly unham- 15 pered by the regulating control embodying my invention. The moment however, that the rear train reaches its minimum of safety distance from the front train, taking into consideration both its own speed and both 20 the distance ahead and the speed of the preceding train, the automatic regulating or controlling switch 16 instantly and automatically places a corresponding limit on the speed of the rear train, varying its limit 25 of speed from moment to moment, as the speed or distance ahead of the preceding train may vary. Moreover, the speed of the rear train is reduced to a point only just within its maximum safety limit at any 30 given instant, and as soon as its speed is reduced to this point the regulating switch again closes and the control of the speed of such trains passes instantly into the full control of the motorman. The instant the 35 speed of the rear train again reaches its limit as governed by the speed or distance ahead of the preceding train the automatic regulating switch again comes into action to cause the speed thereof to be again re- 40 duced. To accomplish this automatic regulation and control of the speed of the rear train the motorman of that train must have his control in "on" position, and when in that position the automatic control device 45 will operate at all times to cause said train to attain and to maintain with safety the maximum speed which the speed and distance ahead of the preceding train will justify, and the motorman of the rear train 50 need not operate his controller until he desires to slow down and stop his train at a station, or for any other purpose, the motorman always retaining full control of his train to do this.

55 In the use of an automatic regulating and control system of the nature referred to, a train may be started out over the same tracks and immediately in rear of a preceding train, and should the motorman of 60 the rear train become disabled, or should neglect his duties, the rear train would follow the preceding train at approximately a constant distance to the rear thereof, and at approximately the same speed thereof, running rapidly, slowing down, stopping and

starting up again, in exact accord with the corresponding movements and operation of the preceding train, and at all time without the slightest danger of a collision. Indeed, if desired, a railway system employing an 70 arrangement embodying my invention might be operated without motormen provided devices, well known in the art, are employed to automatically slow down and stop trains at stations, and to start the train again when 75 all the doors are closed. And in any event the use of the invention enables trains to be operated with perfect safety at much more frequent intervals and at greater reduction of headway or distance apart than is possible with systems heretofore employed, 80 thereby greatly increasing the carrying capacity as well as the safety operation of the railway system.

If desired, and as a precautionary safety 85 feature, a suitable indicator 22, placed in the circuit of the solenoid 8, and located in convenient proximity to the motorman's controller E, may be employed. With such an indicator or other form of signal device, so 90 located and arranged, it will be understood that the motorman is instantly warned in case the electrical connection through solenoid 8 should become opened for any reason. In such event the motorman will know that 95 he cannot rely on the operation of the automatic control feature but must depend upon his own care and watchfulness in connection with the devices, signaling arrangements, or block systems ordinarily employed. So long 100 as the indicator device 22 is in proper operation and operates correspondingly to the variations in speed of his own train, the motorman knows that the automatic regulating and control devices are in safe working condition. Of course varying the speed of a 105 train will not of itself affect the signal or indicating device, except as such speed variation might result in varying the distance apart of successive trains.

While I have shown in Fig. 1 and have described in detail of arrangement and operation one form of practical embodiment of my invention it is to be understood that in its broadest scope as defined in the claims, 115 my invention is not to be confined to the particular arrangement above described. Thus, in Fig. 2, I have shown another practical and operative embodiment of my invention, which, in some respects I prefer to 120 employ in practice. In this form of my invention the same general principles are followed and the same general arrangement is employed as above described, and I need not describe again the features in Fig. 2, which 125 are common to the arrangement shown in Fig. 1.

In the arrangement of Fig. 2 I have changed somewhat the wiring connections of the solenoids which control the regulating 130

and controlling switch 16. These solenoids are designated, respectively, by reference numerals 30 and 31, in Fig. 2 the solenoid 30 acting to maintain the switch 16 closed while the solenoid 31, acts to open said switch.

In the arrangement of Fig. 2 I dispense with the resistances intermediate adjacent sections of the conductor 17 and in place thereof I connect each section of said conductor to ground through a resistance indicated at 32, thereby providing a leak circuit connection to ground through the resistance mentioned.

The same arrangement, relation and operation of switches between adjacent sections of conductor 17, as above described, is employed in the form of my invention shown in Fig. 2, that is, all of said switches are closed both in front of and to the rear of each train, but are open between the front and rear ends of a train.

The speed controlled rheostat arm 2 is provided with a conductor portion 35, which operates over the strips 4 and 6, to bridge the space therebetween, and, in addition, said arm is provided with an insulated conductor portion 34, which operates to bridge the space between the sectional contact strip 5, and an additional continuous conductor strip 33.

The wiring arrangement in this form of my invention includes the following circuits:

From shoe 20, which operates on the third rail or supply conductor, through wire *a*, to strip 4, through conductor portion 35, to sectional strip 6, thence through wire *f*, and solenoid 31, to ground. The relation of the arm 2 and the sectional strip 6 is such that the faster the train is running the less resistance is included in this circuit in the rheostat coils of sectional strip 6. That is, the closer will be the approach of the conductor portion 35, to the end of the strip to which the wire *f* is connected. This means that the faster the train is running the stronger will be the current through solenoid 31, and therefore the greater the effort exerted by said solenoid tending to open the switch 16.

Also from main current supply contact or shoe 20, a circuit connection is completed through wire *g*, solenoid 30, wire *h*, indicator or signal device 22, if one is used, to the forward contact member 18, and thence to the sectional conductor 17. The current flowing in this circuit cannot pass toward the rear of the train because the switch device connecting the conductor section on which contact member 18 is operating, to the section immediately in the rear thereof, is open, as above explained. This current therefore passes to the conductor sections forward of the front end of the train, all of which are in electrical connection with each other because their connecting switches are

closed. Consequently this current leaks off into ground through the resistances 32. If there is no train ahead on the same track for a long distance, then all the switches of sectional conductor 17 for a corresponding long distance ahead will be closed and there will be, consequently, a large number of grounded resistance leak paths in the circuit which includes the solenoid 30, and hence the resulting comparatively free flow of current through solenoid 30, will energize said solenoid and cause the same to hold switch 16, closed even though the train may be operating through a high speed with solenoid 31 correspondingly energized. If, however, there is a train only a short distance ahead, then the current in the circuit of solenoid 30, will not pass any great distance ahead along sectional conductor 17 before it will encounter a switch which has been opened by the preceding train. This will reduce the leak paths to ground and hence will correspondingly reduce the strength of the current flowing through solenoid 30, thereby allowing solenoid 31 to operate to open the switch 16 if the rear train is running at too high a speed with regard to the distance ahead of the preceding train.

When the current passing forwardly along the sectional conductor 17, reaches the rear contact member 19 of the preceding train, it flows through the following circuit: from contact member 19, wire *b*, to rheostat strip 5, conductor bridge 34, and strip 33, to ground. The connection of this circuit to the strip 5, is at that end of the latter which includes the least rheostat resistance *R* when the train is operating at its highest speed, this resistance increasing or being cut in as the speed of the train decreases. If, therefore, the preceding train is traveling at a slow speed, a large amount of rheostat resistance is cut into the circuit of solenoid 30 of the succeeding train, and hence but very little, if any additional current will flow through the circuit of solenoid 30, over and above what was flowing through said solenoid due to the leak path to ground. This latter element, of course, is controlled by the distance apart of the trains. If, however, the preceding train is traveling at a high speed then more of the rheostat resistance will be cut out of the circuit of solenoid 30, with the result of increasing the flow of current through said solenoid.

It will be seen, therefore, that in this arrangement, as in that shown in Fig. 1, the speed of the rear train is governed, regulated and controlled automatically by the joint action of the distance apart between said train and the preceding train and the speed of the latter; the faster the preceding train is running and the farther it is ahead, the faster the following train is al-

lowed to run, while the slower the front train and the closer the rear train is to it, the slower the rear train is allowed to run.

An advantage of the arrangement shown in Fig. 2 over that shown in Fig. 1 is that in Fig. 2 if any of the switches of the sectional conductor 17 should fail to operate properly, or if the contact member 19 on the front train, or the member 18 on the rear train should fail, for any reason, the result would be to decrease the current flow in the circuit of solenoid 30, of the rear train, thereby permitting switch 16 to open under the action of solenoid 31, thereby causing the rear train to slow up and stop, whereas such a failure in the case of the arrangement shown in Fig. 1 would prevent the switch device 16 to operate properly in the performance of its function.

20 In Figs. 3 and 4, I have shown still another arrangement which embodies the broad principles of my invention, and wherein I dispense with a sectional conductor. In lieu thereof, in this arrangement I employ a series of switch devices F, G, H, located at desired distances apart along a railway track.

Associated with each switch device is a pair of movably mounted shoes 36, 37. These shoes are respectively supported on pivoted parallel arms 38, 39, and 40, 41, the two sets of arms being connected together by a rod 42, or otherwise, in such manner that when one shoe is raised the other is lowered, each shoe, in the movements thereof, moving in lines parallel to itself. The shoes are operated by an arm or projection from a passing car or train which engages one of said shoes but not the other. I have not shown a car or train nor the arm or projection referred to but it will be understood that as the train passes by a switch device F, G, or H, the shoe 37, will be engaged and depressed by such an arm or projection, such movement resulting in raising the other shoe 36. The extent of the depressing movement of shoe 37 when a train passes thereby will depend upon the position of elevation which said shoe may occupy at the time.

50 At the front end of each train is carried rollers or studs 43, 44, arranged to be engaged and shifted by the shoe 36 as the train passes thereby. The stud or roller 43, controls a pawl 45, which cooperates with a ratchet 46, while the stud or roller 44, controls said ratchet. In the form shown the stud 44, is carried by an arm 47 which is pivoted at 48, the ratchet 46 being in the segment of a circle. When the stud 44 is engaged and shifted by the shoe 36, the ratchet 46 is rotatively displaced to an extent corresponding to the degree to which the stud is shifted, and is held in rotative displacement by the pawl 45. When the stud 43 is shifted the pawl 45 is actuated to release the

ratchet 46. A suitable connection, a portion of which is indicated at 49, operated by the arm 47, or the pivot 48, thereof, or other associated part, is designed to connect with the car controller, not shown, in such manner that the greater the extent of movement of stud 44, the slower the train is permitted to operate.

A conductor 50 is extended along the track and receives current from the third rail or other current supply conductor 51. The current is supplied from conductor 51 to the conductor 50 intermittently. A simple arrangement is shown wherein a rotating commutator 53, driven by a motor 54 is interposed electrically between the conductors 50, 51, and this commutator operates to periodically interrupt the circuit connection between said conductors. Of course any other suitable form of circuit interrupter operating at a constant rate would answer the desired purpose.

At each switch device F, G, H, is arranged a switch arm 55, each arm arranged to control the pairs of contacts 56, 57, 58, 59. 90 Each arm 55 is raised into position to close circuit through the pairs of contacts 56, 57, 58, and lowered into position to close circuit through contacts 59, by means of a weighted lever 60, which is pivotally mounted and arranged to rock with the rocking arms 38, 39, which carry the shoe 36, as, for instance by being carried on the some pivot support 61 therewith. Thus it will be seen that the extent of rocking movement of the lever 60 100 will depend upon the extent to which the shoe 36 is projected, and this, in turn, is dependent upon the extent to which the shoe 37 is depressed by a train passing the same.

When the weighted lever 60 is raised to 105 its highest position, as shown at switch H, it is retained in that position by a detent 62 which is controlled by a magnet 63, the latter operating, when energized, to release the detent. When not in its highest position, 110 the lever 60 rests upon the upper end of a ratchet bar 64, which is arranged to move vertically in suitable guides, not shown, and which is raised step by step through the actuation of a latch 65, the operation of 115 which is controlled by a solenoid or magnet 66. The rack bar is retained at each step of its raising movements by a detent 67, which is released by the actuation of a magnet 68. When the detent 67 is released the 120 rack bar 64 is permitted to drop down to its lowest position. When in its lowest position the rack bar opens an electric circuit through contacts 69, which contacts are normally closed upon each other when the rack 125 bar is raised from its lowest position.

I will now describe the wiring connections concerned in the operation of this form of embodiment of my invention, and the operation of the system.

Suppose a train is traveling in the direction indicated by the arrow. The stud on the train will engage and depress the shoe 37 at a switch point, say at the switch H, and will correspondingly raise shoe 36. thereby rocking lever 60 until it is caught by detent 62. This places the parts in the position shown at H. This action and operation takes place at each switch point F, G, H etc., past which the train runs. The moment lever 60 is locked in its raised position it completes a circuit from conductor 50 through wire 79, contacts 56, wire 71, solenoid 66, and wire 72 to ground. Since a periodic or intermittent current is supplied to this circuit the solenoid 66 will be successively energized as long as the circuit just traced remains closed. The resulting actuations of latch 65, will cause the rack bar 64 to be raised step by step, say one tooth at every actuation of the latch. The time rate or periods of current of flow may be so adjusted as to cause the actuations of the latch 65 at definite time intervals. When the train reaches the next switch arrangement say switch H, and has raised the lever 60 at that switch the following circuit is completed: from the supply conductor 51, wire 73, contacts 57, wire 74, magnet 63; at the next preceding switch arrangement which the train has passed, say switch G, wire 75, contacts 58, at that switch to ground. This causes the detent 62 at switch G to be withdrawn from lever 60 at that switch, and since the levers 60 are weighted said lever will rock downwardly till it is arrested by the rack bar 64. Now the distance to which lever 60 will rock down, that is, the height of rack bar 64 will be determined by the number of times the latch 65 has operated. This, in turn, will depend upon the number of current impulses sent to the circuit of solenoid 66, and since these impulses are sent at a fixed and definite time interval apart, the height to which the rack bar 64 at switch G, is raised will be dependent upon the time required for the train to travel from switch G to switch H, and this is dependent upon the distance apart of the two switches as well as the speed of travel of the train. This result flows from the fact that step by step elevation of the rack bar 64 at any switch commences with the closing of the circuit of the solenoid 66 at that switch, through the contacts 56, that is, by the passage of the train by said switch, and which step by step elevation terminates when the train reaches the next switch ahead and closes the circuit of the release magnet 63 of the preceding switch, through the closing of the contacts 57 at said switch ahead. Of course this operation is carried out in successive order as the train passes the switches F, G, H, etc. The slower the train

travels from one switch to the next the higher the bar 64 will be raised at the preceding switch and therefore the less will be the distance the arm 60 will descend at that switch when released by its associated detent 62, and consequently the less will the shoe 36 be withdrawn, and consequently the greater will be the extent to which the roller 44 of the next succeeding train will be raised, and hence the greater will be the extent to which the speed of said succeeding train is reduced. Thus it will be seen that the speed of the following train, if following closely upon the heels of a preceding train, will be limited by the speed of the preceding train and the distance it is ahead, while leaving the following train free to travel safely at any desired speed provided the preceding train is far enough ahead.

It will be observed that the circuit of each release magnet 63 is closed to ground through the contact 58 of its own switch arrangement, and consequently this circuit is opened when the arm 60 is released. Therefore the closing of this circuit to release the arm is only momentary.

When the arm 60 is released by the detent 62 and drops till it is arrested by the rack bar 64, in whatever position of elevation said bar may occupy, the contacts 59 are closed. This closes the following circuit: From supply conductor 51, through wire 76, contacts 59 at switch H, for example, wire 77, magnet 68, of switch G, wire 78, switch 69, to ground. The switch 69 is closed only when the rack bar 64 is raised from its extreme retracted or released position. The closing of this circuit releases the detent 67, and permits the rack bar to descend to its lowest position thereby opening the contact 69. The lowering of this bar to its lowest position allows arm 60 to drop to its lowest position which results in retracting shoe 36 to its lowest position. Consequently when a train reaches any switch F, G, H, etc., it instantly sets the shoe 36 at that switch into position to cause an immediately following train to be automatically stopped, while at the same time causing the elevated shoe 36 at the next rearward switch to be moved into such position as to automatically reduce the speed of an immediately following train, depending upon the speed and distance ahead of the preceding train, or the time interval which has elapsed from the passage of the preceding train between two adjacent switches. At the same time it drops the shoe 36 of the second rearward switch to its lowest position, thereby allowing a following train to freely pass it.

It will be understood that the drawings are largely diagrammatic illustrations of arrangements embodying the principles of my invention, and that the details may be

varied in many ways and throughout a wide range without departure from the spirit and scope of my invention.

But having now set forth the objects and nature of my invention, and various arrangements for carrying the same into practical operation, what I claim as new and useful, and of my own invention, and desire to secure by Letters Patent of the

10 United States, is:—

1. In a railway block system, the combination with a train, of means controlled by the speed thereof for controlling the speed of a following train.
2. In a railway block system, the combination with a train, of means controlled conjointly by the speed and the distance apart of said train and a following train for controlling the speed of the latter.
3. The combination with a train having a speed controller device, of means controlled by the speed of another train operating on the same tracks for automatically operating said device.
4. The combination with a train having a speed controller device, of means controlled conjointly by the speed and distance ahead of another train operating on the same tracks for automatically operating said device.
5. In a block system for railway trains, a train, a speed controller device thereon, electrical devices for controlling said controller device, and means controlled by the speed of another train operating on the same tracks for automatically controlling said electrical devices.
6. In a block system for railway trains, a train, a speed controller device thereon, electrical devices for controlling said controller device, and means controlled conjointly by the speed and distance ahead of another train operating on the same track for automatically controlling said electrical devices.
7. In a block system for railway trains, a train, a speed controller therefor, a switch for controlling said controller, and means controlled by the speed of another train operating on the same tracks for operating said switch.
8. In a block system for railway trains, a train, a speed controller therefor, a switch for controlling said controller, and means controlled conjointly by the speed and distance ahead of another train operating on the same tracks for operating said switch.
9. In a block system for railway trains, a train having an automatic speed controller and a manually operated controller, and means controlled by the speed of another train operating on the same tracks to actuate said automatic controller independently of the manual controller.

10. In a block system for railway trains, 65 a train having an automatic speed controller and a manually operated controller, and means controlled conjointly by the speed and distance ahead of another train operating on the same tracks to actuate said automatic controller independently of the manual controller.

11. In a block system for railway trains, a train having an automatic speed control device, electrical devices for controlling 75 said control device, circuits for said electrical devices, and means controlled conjointly by the speed of said train and that of another train operating on the same tracks for controlling said circuits.

12. In a block system for railway trains, a train having an automatic speed control device, electrical devices for controlling said control device, circuits for said electrical devices, and means controlled conjointly by 85 the speed of said train and speed and distance ahead of another train operating on the same tracks for controlling said circuits.

13. In a block system for railway trains, 90 a train, a speed controller therefor, an electric circuit for controlling said controller, means controlled by the speed of said train for controlling said circuit, a second circuit for controlling said controller, and 95 means controlled by the speed of another train operating on the same tracks for controlling said second circuit.

14. In a block system for railway trains, a train, a speed controller therefor, an electric circuit for controlling said controller, means controlled by the speed of said train for controlling said circuit, a second circuit for controlling said controller, and means controlled by the distance ahead of another 105 train operating on the same tracks for controlling said second circuit.

15. In a block system for railway trains, a train, a speed controller therefor, an electric circuit for controlling said controller, means controlled by the speed of said train for controlling said circuit, a second circuit for controlling said controller, and means controlled conjointly by the speed and by 110 the distance ahead of another train operating on the same tracks for controlling said second circuit.

16. In a block system for railway trains, a train, a speed controller therefor, means controlled by the speed of the train normally tending to cause the speed controller to reduce the speed of the train and means controlled by the speed of another train operating on the same tracks normally tending to cause said speed controller to allow 120 an increase of the speed of the first mentioned train.

17. In a block system for railway trains,

- a train, a speed controller therefor, means controlled by the speed of the train normally tending to cause the speed controller to reduce the speed of the train, and means controlled by the distance ahead of another train operating on the same tracks normally tending to cause said speed controller to allow an increase of the speed of the first mentioned train.
18. In a block system for railway trains, a train, a speed controller therefor, means controlled by the speed of the train normally tending to cause the speed controller to reduce the speed of the train, and means controlled conjointly by the speed and distance ahead of another train operating on the same tracks normally tending to allow an increase of the speed of the first mentioned train.
19. In a block system for railway trains, a train, a speed controller therefor, and means controlled by the opposing action of the relative speed of the said train and that of another train on the same tracks for controlling said speed controller.
20. In a block system for railway trains, a train, a speed controller therefor, and means controlled by the opposing action of the relative speed of the said train, and the conjoint action of the speed and distance ahead of another train operating on the same tracks for controlling said speed controller.
21. In a block system for trains, a train having a speed controller, an electrical device normally acting to operate said controller, a circuit for said device, said circuit including a sectional conductor alongside the track on which the train operates, a contact shoe operating along the conductor, and means whereby the amount of energization of said electrical device is dependent upon the number of sections of the sectional conductor through which the circuit passes.
22. In a block system for trains, a train having a speed controller, an electrical device normally acting to operate said controller, a circuit for said device, said circuit including a sectional conductor alongside the track on which the train operates, a contact shoe operating along the conductor, switch devices for connecting adjacent sections of said conductor, said switch devices operated by the passage of the train therepast, and means whereby the amount of energization of said electrical device is dependent upon the number of sections of the sectional conductor through which the circuit passes.
23. In a block system for trains, a train having a speed controller, an electrical device normally acting to operate said controller, a circuit for said device, said circuit including a sectional conductor alongside the track on which the train operates, a contact shoe operating along the conductor, ground connections for the sections of said conductor, and means whereby the amount of energization of said electrical device is dependent upon the number of sections of the sectional conductor through which the circuit passes.
24. In a block system for trains, a train having a speed controller, an electrical device normally acting to operate said controller, a circuit for said device, said circuit including a sectional conductor alongside the track on which the train operates, a contact shoe operating along the conductor, said conductor adapted to receive current through another train operating on the same tracks, the sections of said conductor, means to vary the resistance in the ground circuit of said shoe, and means whereby the amount of energization of said electrical device is dependent upon the number of sections of the sectional conductor through which the circuit passes.
25. In a railway block system, the combination with a train, of means controlled by the speed thereof for controlling the speed of a following train without affecting the speed of said first mentioned train.
26. In a railway block system, the combination with a train, of means controlled by the speed thereof for limiting the maximum speed of a following train.
27. In a railway block system, the combination with a train, of means controlled by the speed thereof for placing a variable limit on the speed of the following train.
- In testimony whereof I have hereunto set my hand, in the presence of the subscribing witnesses, on this 8th day of July, A. D. 1915.

HAROLD ROWNTREE.
